UNITED STATES PATENT OFFICE.

GEORGE H. WEEKS, OF AURORA, NEW YORK, ASSIGNOR OF ONE-HALF HIS
RIGHT TO CHARLES B. GOULD, OF SAME PLACE.

IMPROVEMENT IN MOWING-MACHINES.

Specification forming part of Letters Patent No. 158,553, dated January 5, 1875; application filed
October 15, 1874.

To all whom it may concern:

Be it known that I, GEORGE H. WEEKS, of Aurora, county of Cayuga and State of New York, have invented a new and useful Improvement in Harvester for Reaping and Mowing; and I do hereby declare that the following is a full, clear, and exact description thereof, reference being had to the accompanying drawings, making part of this specification, in which—

Figure 1 is a top view of my improved harvester. Fig. 2 is a longitudinal section of the same in the line $x\ x$ of Fig. 1, looking toward the outer grain-divider. Fig. 3 is a longitudinal section in the line $y\ y$, Fig. 1, looking toward the drive-wheel. Fig. 4 is a vertical longitudinal section of the machine in the line $z\ z$ of Fig. 1. Figs. 5 and 6 are views of the device for reciprocating the sickle. Figs. 7 and 8 are views of the device for coupling the sickle to its driving-head. Fig. 9 is a view of the combined caster-wheel and tongue-iron.

The nature of my invention consists, first, in the combination of the draft-frame to which the cutting apparatus and its driving mechanism is attached with the stirrup or crank-arm of the drive-wheel, in such manner that the usual united adjustment of the draft-frame and the stirrup, and the independent adjustment of the draft-frame and cutting apparatus, may be effected; and while this is the case, the strain of the pull and resistance upon the machine is removed from the axle of the power-transmitting pinion to the axle of the drive-wheel, and thus the operation of the gearing is not interfered with, and danger of breaking the pinion-shaft avoided. Second, it consists in the combination of the draft-frame, tongue, caster-wheel, and adjusting-lever in such a manner that the fulcrum of the lever is located forward of the shaft of the caster-wheel, upon the hinging-iron of the tongue, and the draft-frame is adjusted upon the hinging-pin of the tongue, and the tongue at the same time is left free to vibrate on said pin, and thus any undue strain upon the draft-pole prevented; third, in the combination of the sickle, having a dovetail on its inner end, a guided driving-head, having a dovetail socket in its top at its outer end, a hooking-coupling, and a fastening-

pin, whereby the head can be introduced to its place, and the two parts united together very conveniently; fourth, in a pendent hanger or bracket of semi-cylindrical form at its bottom, applied on the under side of the bed-plate of the draft-frame in line with the cutting apparatus, said hanger having end bearings for a short shaft and side ledges, which form grooves in its bottom to receive and confine the driving-head of the sickle, it also serving for supporting the cutting apparatus and the device which reciprocates the sickle, and for shielding said device and the small pinion which is on the shaft with it; fifth, in the combination of two disks of elliptical or oval form, set diagonally on a shaft within the hanger, with their faces parallel to each other, in combination with the sickle-head, having a vertically-sliding and horizontally-rotating ball fastened to its heel, and with a pinion which receives rotary motion from the drive-wheel for the purpose of moving the sickle back and forth without any lost motion, and without the great friction experienced from the employment of spiral threads, such as are formed on a screw.

In the accompanying drawings, A represents an ordinary driving-wheel, having a toothed spur-ring, B, on its inner face. The teeth of ring B may be on the inner or outer circumference of the ring. The wheel A is fitted on a short axle, C, and on the outer end of this axle the driver's seat C' is mounted. D is the stirrup or crank-arm of the axle C. This arm and the axle vibrate together. E is the draft-frame, constructed with a segmental arched bracket, E', on its outer side. F is a pinion-shaft, arranged in boxes $a\ a$ of the draft-frame. To this shaft the stirrup D is hinged loosely, the passage b in the stirrup, through which the shaft passes, being elongated, so as to allow the shaft back and forward play in the direction of the pull and resistance on the machine. By this means the strain and pull are prevented from coming upon the pinion-shaft, as will presently be explained. G G are shoulders or offsets on the outer side of the stirrup. These shoulders are immediately under the arched segmental bracket, and when the draft-frame is pulled forward and

the stirrup held back by the traction of the wheel, the arched bracket bears firmly against these offsets, and thus the strain and resistance is removed from the pinion-shaft F and transferred to the axle C of the drive-wheel. H is a pinion on the outer end of the axle for receiving the power from the toothed ring B of the drive-wheel. I is an ordinary clutch, and I' the clutch-lever for throwing the pinion in and out of gear with its shaft F—that is, making the pinion either fast or loose on its shaft, as may be desired. The draft-frame and stirrup are to be, as usual, constructed so as to permit the bodily adjustment of the cutting apparatus with the stirrup. J is a bracket, pendent from the under side of the draft-frame. This bracket is in form of an inverted arch, and its bottom portion is a true semi-cylinder. At the ends of this bracket bearing-boxes c c are formed, and on its bottom under-beveled side ledges d d are fastened or cast, so as to form a central groove, f, and side grooves f' f'. K is a short shaft fitted in the boxes c c, so as to revolve but not to move longitudinally. On this shaft the device L L¹ L², for moving the sickle, is placed diagonally, as shown. The plates L¹ L² of this device are elliptical or oval in form, and have their faces parallel to each other when on the shaft K. These plates are fastened to the parallel faces of the diagonal hub L by means of screws e e, so that they may be removed, and the faces of the hub ground off, so as to have the plates set nearer together. This becomes necessary when the parts wear so as to leave play room. M is the sickle-head, made with beveled edges, which fit under the ledges d d of the grooves f', formed in the bottom of the bracket J. This head has a vertical pin projecting up from its heel, and on this pin a spherical ball, N, is loosely fitted, so as to revolve freely and slide up and down slightly. The ball plays between the diagonal plates L¹ L², and as the shaft revolves the faces of the plates impinge successively upon the ball, one plate moving the ball and head to the right and the other to the left, and whatever may be the position of the plates the bearing upon the ball will always be maintained by one or the other of the same. The motion of the shaft is produced by means of the pinion O on its outer end gearing with the pinion O' on shaft F, which carries the pinion H, which gears with the spur-ring B of the drive-wheel. The finger-bar is rigidly fastened to the bracket J, and its sickle is coupled to the head M by means of a dovetail, g, on the inner end of the sickle, which fits in a dovetail socket, h, of the head, and is fastened in position by a hooking-coupling, i, and a pin, j, as shown in the drawings. By this means of connecting the sickle to the head, facilities for removing the sickle for sharpening or other purpose, without disturbing the other parts, are secured, and convenience in first attaching the head and sickle to the machine is afforded. The tongue or draft-pole S of the machine is con-

nected by a hinge-pin to the forward-extending brackets k k of the box P, in which the caster-wheel P' swivels, said box P being fastened to the front end of the draft-frame, or cast thereon, as may be found most desirable. The adjusting-lever Q of the caster-wheel is extended from the rear of the draft-frame, and its forward end, which is forked, is pivoted to the gimbal-joint box t of the caster-wheel, and also to a pin passed through two ears, m m, cast on the top of the brackets k k, as shown in the drawings. The rear end of this lever is, as usual, looped around a perforated standard, R, and by means of a pin inserted through the lever and the standard, any adjustments which may be made are retained as long as desired.

It will be noticed that the rear end of the tongue is on the same fulcrum that the brackets k k swing on, and therefore, when the lever is depressed, the caster-wheel will be lowered and the frame raised without binding the tongue or interfering with its free motion.

One great advantage in the construction of the device which reciprocates the sickle of oval plates is, that the hanger in which it rotates may be made much smaller in diameter than if the plates were made of circular disks.

It will be understood that the orbit of the elongated plates, set diagonal, is no greater than the diameter of the cylinder from which they are cut diagonally. Therefore, while the elliptical plates give a great length of throw to the sickle back and forth, they do not require any more room than is required for their shorter diameter to move in.

What I claim as my invention is—

1. The combination of the segmental bracket E', stirrup D, elongated passage b, bearing-offsets G, pinion-shaft F, and axle C, whereby the stirrup, notwithstanding it is fitted upon the pinion-shaft, and is capable of raising and lowering it as required, is prevented from pulling upon and straining said shaft F when the machine is in operation, substantially as set forth.

2. The combined caster-wheel and draft-pole iron, constructed with a swivel-box, P, for the shaft of the caster-wheel to swivel in, with two hinging-brackets, k, for the draft-pole to hinge upon, and with two ears, m, for the adjusting-lever Q to be pivoted to, in combination with the tongue S, the caster-wheel P', the draft-frame E, and the adjusting-lever Q, substantially in the manner and for the purpose described.

3. The combination of the dovetail g on the end of the sickle-bar, the dovetail socket h in the driving-head M, the hooking-coupling i, and the pin j, substantially in the manner shown and described.

4. The inverted arch-shaped pendent hanger J on the under side of the bed-plate of the draft-frame, and in line with the cutting apparatus, constructed with end bearings for a short shaft, and with guiding-ledges on its bottom to confine and guide the driving-head

of the sickle, and serving for supporting the cutting apparatus and the device which reciprocates the sickle, and also shielding said device and the pinion, which is on the same shaft with it, substantially as and for the purpose described.

5. The sickle-driver arranged on the pinion-driving shaft K, and within the hanger J, formed of two oval disks, L¹ L², which are placed diagonally on the shaft a short distance

apart, with their faces parallel, in combination with the ball N on the perpendicular extension of the heel of the sickle-bar, and passed directly into the groove formed between the working faces of the disks, substantially in the manner and for the purpose described.
